UNITED STATES PATENT OFFICE.

CHESTER T. ALLCUTT, OF PITTSBURGH, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed May 12, 1919. Serial No. 296,354.

To all whom it may concern:

Be it known that I, CHESTER T. ALLCUTT, a citizen of the United States, and a resident of Pittsburgh, in the county of Allegheny and State of Pennsylvania, have invented a new and useful Improvement in Lightning Arresters, of which the following is a specification.

My invention relates to spark-gap electrodes and particularly to apparatus of this character, as employed in lightning arresters.

In the accompanying drawings, Fig. 1 is a sectional view of a spark-gap device constructed in accordance with my invention; Figs. 2, 3 and 4 are slight modifications thereof.

Heretofore, it has been customary to construct spark-gap electrodes of a metal, such, for example, as brass, which has the property of requiring a relatively high voltage to maintain an arc between the two electrodes so constructed. The advantage of using electrodes of this character, in preference to metals not possessing this property, is that a smaller number of gaps, connected in series, is required to suppress a power arc following an overvoltage discharge.

By my invention, I provide spark-gap electrodes composed of a material which is a very good electrical conductor at relatively low temperatures and a very good insulator at relatively higher temperatures so that, when a discharge occurs between two spaced electrodes, the particular point at which the discharge leaves and enters the electrodes will be heated thereby and immediately render it of considerably higher resistance, thereby serving to break down the discharge or, if over-voltage still exists on the line, to cause it to seek a new discharge path. This results in a particularly effective suppression of an arc between two electrodes of the nature described.

For a better understanding of my invention, reference may now be had to the accompanying drawings in which I show a metal casing 1 provided with an insulating cover 2 and containing a material 3 which constitutes one of my electrodes and may be composed of lead peroxid preferably combined with some inorganic binder, such as sodium silicate. A similar electrode 4 composed of similar material is attached to the

cover member 2 by means of a conducting member 5 extending therethrough. The electrode 4 is connected to a line 6 through a terminal 7 and the casing 1 is connected to ground 8 by means of a terminal 9.

Fig. 2 is a modification of my invention in which two electrodes 10 and 11 are connected to a line 12 and ground 13, respectively, and which are provided with coatings of lead peroxide or some material of similar properties. The electrodes 10 and 11 are mounted upon metallic supports 14 which, in turn, are mounted upon a common insulating base 15.

Fig. 3 shows another modification of my invention in which a body of lead peroxid 16 is disposed within a cup shaped member 17 and may be in the form of a powder. The other electrode 18 is a metallic plate. This form of my invention is particularly suitable for direct current, under which conditions the lead peroxid should be made the cathode.

Fig. 4 shows still another modification of my invention in which two horn-gap electrodes 19 and 20 are each provided with a coating 21 of lead peroxid.

From the foregoing description of my invention, it will be obvious to those skilled in the art that any small discharge of current between the electrodes will be carried thereby without producing any change in the lead peroxid on account of relatively small amount of heat generated thereby, while, with a relatively heavy discharge of current, the heat generated thereby will immediately transform the lead peroxid into a lower oxid of relatively poor electrical conductivity, thus increasing the resistance of the path of the discharge. Eventually, the resistance of the path will become such that the voltage will be insufficient to maintain a discharge therethrough and either the discharge will be broken thereby or a new discharge path will be found, if the voltage is still sufficiently above normal.

It will be understood that, for line voltages higher than the maximum on which a single gap will function effectively, two or more gaps of the nature described may be employed and connected in series relation.

While I have described my invention in a plurality of forms, it will be obvious to those skilled in the art that it is not limited to

those set forth but is susceptible of various minor changes and modifications without departing from the spirit thereof and I desire, therefore, that only such limitations shall be placed thereupon as are imposed by the prior art or are specifically set forth in the appended claims.

I claim as my invention:

1. A discharge-gap member comprising a conducting member provided with a coating of conductive oxid which becomes converted by heat into a different oxid of higher electrical resistance.
2. A discharge-gap member comprising a conducting member provided with a coating of a metal compound which becomes converted by heat into a compound of high resistance.
3. A discharge-gap member comprising a conducting member provided with a coating of a metal compound of low-heat conductivity and low electrical resistance which becomes converted by heat into a compound of different chemical composition and high electrical resistance.
4. A discharge-gap member comprising a

conducting member provided with a coating of lead peroxid.

5. A discharge-gap member comprising a conducting member provided with a coating of material comprising lead peroxid and a binder.

6. A discharge-gap member comprising a conducting member provided with a coating of material comprising lead peroxid and sodium silicate.

7. A lightning arrester comprising a plurality of spaced discharge members, one of said members being provided with a coating of lead peroxid.

8. A lightning arrester comprising two spaced discharge members, one of said members being connected to a source of supply and the other being connected to ground and provided with a coating of lead peroxid.

9. A lightning arrester comprising two spaced discharge members, each provided with a coating of lead peroxid.

In testimony whereof, I have hereunto subscribed my name this 24th day of April, 1919.

CHESTER T. ALLCUTT.
